(57) CLAIM

The ornamental design for a tabletop with handle, as shown and described.

DESCRIPTION

The patent or application file contains at least one drawing executed in color. Copies of this patent or patent application with color drawings will be provided by the Office upon request and payment of the necessary fee.

FIG. 1 is a perspective view of a first embodiment of a tabletop with handle showing my new design;

FIG. 2 is an enlarged detailed perspective view taken from the boxed area 2 shown in FIG. 1;

FIG. 3 is a perspective view of a second embodiment of a tabletop with handle showing my new design; and,

FIG. 4 is an enlarged detailed perspective view taken from the boxed area 4 shown in FIG. 3.

The broken lines illustrate portions of the tabletop with handle that form no part of the claimed design.
